Attorney

UNITED STATES PATENT OFFICE

GEORGE B. RAYBURN, OF LOS ANGELES, CALIFORNIA, ASSIGNOR OF ONE-HALF TO
ALBERT E. MARDON, OF LOS ANGELES, CALIFORNIA

BATHING HAIR NET

Application filed November 11, 1929. Serial No. 406,390.

This invention relates to bathing hairnets, and an object of the invention is to provide for maintaining the hair in place while bathing.

Another object of the invention is to provide a hairnet of the character referred to that is normally disposed in a plane so as to facilitate the package and storage thereof.

Further objects of the invention are to provide, in a manner as hereinafter set forth, a bathing hairnet of the character referred to, which is strong, compact and durable, thoroughly reliable for its intended purpose, very easily applied to the head without detracting from the appearance and is comparatively inexpensive to manufacture.

With the foregoing and other objects in view, the invention consists of the novel construction, combination and arrangement of parts as will be hereinafter more specifically described and illustrated in the accompanying drawings, wherein is disclosed an embodiment of the invention, but it is to be understood that changes, variations and modifications may be resorted to without departing from the spirit of the claims hereto appended.

In the drawings, wherein like reference characters denote corresponding parts throughout the several views:

Figure 1 is a part plan and part diagrammatic view of the hairnet in accordance with the present invention, removed from the head.

Figure 2 is an edge view thereof.

Many bathers desire to swim without using the conventional swimming cap, preferring the hair to get wet. It has been the experience of bathers to be annoyed by the hair becoming disarranged and flowing into the eyes and preventing proper vision as well as annoyance. The present invention will eliminate the annoyance of flowing hair during bathing and at the same time, will permit sun and air to contact with the hair which is prevented in the modern bathing cap.

Bearing the foregoing in mind, and referring to the drawings, 3 indicates generally the bathing hairnet structure, removed from the head and not under tension. The bathing hairnet consists of an outer circular rim 4 that when applied to the head, encircles

the head at a point about the forehead. The inner circular rim is indicated at 5 and is considerably less in diameter than the outer rim 4.

When the hairnet is not under tension, the rim 4 and rim 5 lie in the same horizontal plane. Disposed between the inner rim 5 and the outer rim 4 are a plurality of radiating ribs 6 the inner ends of which are secured to the outer periphery of the inner rim 5 and the outer ends of said ribs 6 are connected to the inner periphery of the outer rim 4.

When the bathing hairnet is not applied to the head, and is not under tension, the ribs 6 are scallop shaped or zig-zag as is shown in Figure 1 of the drawings. When the hairnet is applied to the head, the inner rim 5 rests on the top of the head, and the outer rim 4 is encircled about the head in the location of the forehead, while the ribs 6 assume a straight line while under tension.

The rims 4 and 5 and the ribs are formed of rubber or other resilient material. It is pointed out that the resistance offered by the scallop-shaped ribs 6 to straightening out under pressure has a peculiar effect of holding the hair securely in place. The tendency of the ribs 6 under tension is to assume the zig-zag shape shown in Figure 1.

The inner rim 5 is concentric with respect to the outer rim 4.

It is to be understood that by describing in detail herein, any particular form, structure or arrangement, it is not intended to limit the invention beyond the terms of the several claims or the requirements of the prior art.

I claim:

1. A bathing hairnet comprising a pair of spaced rims, ribs radiating from one rim to the other, and said rims and ribs arranged to lay in the same plane when not under tension.

2. A bathing hairnet comprising an outer rim, a body of smaller area than the rim disposed within an area generated by the rim, resilient ribs connecting the said rim and body together, and said rim, body and ribs arranged to lay in the same plane when not under tension.

3. A bathing hairnet comprising a resilient outer rim, a resilient body of smaller area

than the rim disposed within an area generated by the rim, resilient ribs connecting the said rim and body together, and said rim, body, and ribs arranged to lay in the same plane when not under tension.

5 4. A bathing hairnet comprising an outer resilient rim, a resilient body of smaller area than the rim arranged concentric with respect to the axis of said rim, resilient ribs connecting the said rim and body together, and said rim, body and ribs arranged to lay in the same plane when not under tension.

10 5. A bathing hairnet comprising an outer resilient rim, a resilient body of smaller area than the rim arranged concentric with respect to the axis of said rim, resilient ribs connecting the said rim and body together, and said rim, body and ribs arranged to lay in the same plane when not under tension, said ribs being 15 scalloped when not under tension and disposed radially with respect to the rim.

In testimony whereof I affix my signature.

GEORGE B. RAYBURN.
